PICTURE FRAME

Jeanne Mertz Fielding, New York, N. Y.

Application November 10, 1951, Serial No. 255,786

13 Claims. (Cl. 40—155)

1

The present invention relates to picture frames, and, more particularly, to an inexpensive picture frame fabricated from sheet material.

Conventional inexpensive picture frames of this type are two-dimensional and, accordingly, have a cheap and flimsy appearance, and lack durability and rigidity. Attempts to fabricate better-looking three-dimensional sturdy frames of sheet material have resulted in relatively complicated and costly structures. The conventional structures include several pieces of material so that a consumer cannot assemble them easily and their manufacture is quite expensive and time-consuming.

It is an object of the present invention to provide a durable and attractive three-dimensional picture frame which is inexpensive to manufacture and easy to assemble.

It is another object of the present invention to provide a picture frame of the character described which simulates more expensive and complicatedly constructed picture frames, e. g. wooden frames.

It is another object of the present invention to provide a blank from which a picture frame of the character described can be fabricated.

Other objects of the present invention will in part be obvious and in part will be pointed out hereinafter.

The invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of the invention,

Fig. 1 is a front view of an assembled picture frame constructed in accordance with the present invention;

Fig. 2 is a rear view of the frame shown in Fig. 1;

Fig. 3 is an enlarged fragmentary sectional view taken substantially along the line 3—3 of Fig. 1;

Fig. 4 is a reduced sectional view taken substantially along the line 4—4 of Fig. 3; and

Fig. 5 is a plan view of a blank from which the frame is assembled.

Pursuant to the present invention a sheet of stiff, tough material such as manila or kraft wrapping paper, cardboard, plastic impregnated or plastic coated paper, parchment, pliable sheet metal or plastic film is shaped into a single

blank 10 formed with fold lines so as to be capable of assembly into a three-dimensional picture frame.

Various shapes of blank will produce differently shaped picture frames. The embodiment set forth below is, therefore, not to be taken as limiting and is merely an example showing how a rectangular frame may be produced.

The blank 10 is cut so as to include two isosceles trapezoidal end panels 12, 14 and two isosceles trapezoidal central panels 16, 18. The meeting end edges of each panel form a crease or fold 20. Each panel has a top flap 22 and a bottom flap 24 joined to the top and bottom, respectively, of the panel by creases 26, and is divided into two sections 28, 30 by a crease 32 parallel to the top of the panel, the sections and flaps being defined by the creases 26, 32. When the blank is assembled into a picture frame, the panels comprise the front of the frame and the flaps the rear of the frame. The crease 32 of each panel is parallel to the top of that panel.

In order to carry out the present invention, the flat blank, before assembly thereof into a picture frame, must be so formed that the portion of the crease 20 at the end of any given section is a straight-line uninterrupted continuation of the portions of the same crease at the ends of the remaining sections in the same panel. Moreover, the ends of the respective sections of particular juxtaposed panels must be coincident with the crease 20 joining such panels in the flat blank. By virtue of this construction, as will appear hereinafter, each corner of the picture frame, save one, will consist of but a single sheet of material every section of which is unbrokenly joined to all contiguous sections. In the preferred form of the invention, as illustrated herein, each panel includes only two sections between the top and bottom flaps and in such form it is critical that said sections 28, 30 should be of substantially the same width.

Each panel forms a straight side 34 of a polygonal picture frame when the blank is assembled and is disposed in the blank with respect to an adjacent panel at an angle α between the top edges of end-to-end connected panels. The size of angle α is a function of both the angle b between the sides 34 formed by the particular adjacent panels and the angle c between the sections 28, 30 when the frame is assembled. Thus frames of different shapes and depths can be fabricated including irregular as well as regular shapes.

Tabs 36, 38 and 40 are provided at the end of

one panel on the top flap and sections thereof. A single tab 42 is provided at the end of the other end panel on the top flap thereof. Between the tabs and their associated sections are creases 44 corresponding to the creases 20.

All of the creases 26, and the creases 44 at the ends of the base sections 30 as well as those portions of the creases 20 at the ends of the base sections 30 fold in the same direction, e. g. in Fig. 5 all of said creases point downwardly from the plane of the drawings. This direction will be designated as "forward" and the surfaces facing in that direction designated as "forward surfaces." The creases 44 at the end of the top sections 28 as well as those portions of the creases 20 at the ends of the top sections 28 point rearwardly.

It will be observed that adjacent top flaps 22 are unconnected, i. e. they are separated from one another by slits.

To assemble the frame from the blank, each section 28 is folded rearwardly with respect to the associated crease 32 and simultaneously each section 30 is folded rearwardly with respect to its associated crease 32. This is done for all of the panels 12, 14, 16 and 18. Thus the sections 28, 30 of each side will form a dihedral angle with the apex thereof pointed forwardly. As the several sections are folded in the foregoing manner the sides will move from the position shown in Fig. 5 to the position shown in Fig. 1, that is to say, forming said sides into dihedral angles will cause the angles between adjacent sides to be reduced so that folding the sections of the sides automatically causes the corners to be brought to the proper angular shape.

It now will be appreciated that each side of the finished frame is composed of a plurality of long flat sections, said sections being set at an angle with respect to one another, this being the dihedral angle aforementioned. It also will be seen that the sections of each side are connected to one another by long crease lines and that the corresponding sections of each side are connected to the corresponding sections of adjacent sides by crease lines, thus insuring that at the corners a solid construction is affected.

The bottom flaps are arranged to lie in back of their associated top flaps. The appearance of the finished frame in front elevation is shown in Fig. 2 and the sectional configuration is best seen in Fig. 3.

The free ends of the end panels are attached to each other by disposing tabs 38 and 40 of one end panel against the rear surfaces of the ends of the sections of the other end panel and securing the tabs thereto in a suitable manner, as for example by gluing or stapling. As shown, the attachment is accomplished by providing areas 46 of glue on the rear surfaces of the sections against which the tabs are adapted to lie. In this way easy assembly is possible. In addition, tab 36 is secured to the rear surface of tab 42 in the same manner as that just described for the other tabs.

When assembled, the rear surfaces of the sections constitute a V-shaped ornamental front of each side of the frame; the top and bottom flaps serve as elements between which the picture to be framed can be disposed. The picture may be retained in place in any conventional manner, for example, by disposing glue on the rear surfaces of the bottom flaps as shown at 48.

Since the sides must be isosceles as only two sections of equal width are employed, the ornamental front will be symmetrical in the embodiment set forth above.

Means to permit hanging of a picture frame on a wall may be provided. As shown, such means comprises a strip of material 49 secured, for example by gluing, to the front surface of one of the bottom flaps. The strip has a free portion 50 in which an opening 52 is fashioned. The opening will serve to fit on any conventional picture frame hook.

Each section forms a face of the ornamental part of a side of an assembled frame, the faces of any given side being disposed at angles other than 180° to each other.

15 The frame as assembled will form a polygonal construction the corners of which are entirely in one piece with the adjacent sides except for one corner. The polygon may be regular or irregular depending upon the type of frame desired.

20 It thus will be seen that there is provided a device which achieves all the objects of the invention and is well adapted to meet the conditions of practical use.

25 As various possible embodiments might be made of the above invention, and as various changes might be made in the embodiment above set forth, it is to be understood that all matter herein described, or shown in the accompanying drawings, is to be interpreted as illustrative and not in a limiting sense.

30 Having thus described the invention, there is claimed as new and desired to be secured by Letters Patent:

1. A blank of stiff, tough sheet material from 35 which a polygonal straight-sided picture frame can be fabricated, said blank comprising a plurality of end-to-end contiguous trapezoidal panels adapted when assembled to form the front portions of the sides of the frame, each front portion having plural flat faces, straight crease lines parallel to the tops and bottoms of the panels and dividing the panels into a plurality of sections, each section being adapted to form a face of that front portion which corresponds to the 40 panel of which said section comprises a part, straight crease lines connecting the ends of contiguous panels, said crease lines extending uninterruptedly from the tops to the bases of said panels, and the angle between contiguous panels being a function both of the angle between juxtaposed faces of the frame and of the angle between the contiguous sides of the frame.

2. A blank as set forth in claim 1 wherein the trapezoidal panels are isosceles and wherein the angles between contiguous panels are equal.

3. A blank of stiff, tough sheet material from 55 which a polygonal straight-sided picture frame can be fabricated, said blank comprising a plurality of end-to-end contiguous trapezoidal panels adapted when assembled to form the front portions of the sides of the frame, each front portion being V-shaped and having two flat faces, straight crease lines parallel to and midway between the tops and bottoms of the panels and dividing each panel into two sections whose widths are approximately the same, each section being adapted to form a face of that front portion which corresponds to the panel of which 60 said section comprises a part, straight crease lines connecting the ends of contiguous panels, and crease lines extending uninterruptedly from the tops to the bases of said panels, the angle between contiguous panels being a function both of the angle between juxtaposed faces of the

frame and of the angle between contiguous sides of the frame.

4. A blank as set forth in claim 3 wherein flaps are joined by straight crease lines to the tops and bottoms of the panels, said flaps being adapted to form the rear of the frame and support a picture.

5. A blank as set forth in claim 3 wherein tabs are provided at the free ends of the endmost panels to join the sections of said panels when the blank is transformed in a picture frame.

6. A three-dimensional polygonal picture frame fabricated from a one-piece integral blank of stiff, tough sheet material, said frame comprising a plurality of straight side members, each of said side members being composed of a plurality of long flat sections, said sections being set at solid angles in relation to each other and being connected by long crease lines, corresponding flat sections of each side member being unbrokenly connected to corresponding flat sections of adjacent side members by crease lines except at one corner whereby each side member is in one piece with the adjacent side members at the corners except for said one corner, and means to join the corresponding flat sections of the two side members at said one corner.

7. A picture frame as set forth in claim 6 wherein the flat sections are approximately equal in width.

8. A picture frame as set forth in claim 6 wherein each side consists of only two flat sections.

9. A picture frame as set forth in claim 6 wherein each side consists of only two flat sections and wherein the sections are approximately equal in width.

10. A picture frame as set forth in claim 6 wherein the flat sections have flaps integrally connected thereto by crease lines.

11. In a three-dimensional polygonal picture frame a pair of straight side members fabricated from one piece of stiff, tough sheet material, each of said side members being composed of a plurality of long flat sections, said sections being set at solid angles in relation to each other and being connected by long crease lines, corresponding flat sections of each side member being unbrokenly connected to corresponding flat sections of adjacent side members by crease lines whereby the side members are in one piece with one another at the corners.

12. In a blank of stiff, tough sheet material from which a polygonal straight-sided picture frame can be fabricated: two end-to-end sets of contiguous trapezoidal panels adapted when assembled to form the front portions of two adjacent sides of the frame, each front portion having plural flat faces, straight crease lines parallel to the tops and bottoms of the panels and dividing the panels into a plurality of sections, each section being adapted to form a face of that front portion which corresponds to the panel of which said section comprises a part, a straight crease line connecting the ends of the contiguous panels, said crease line extending uninterruptedly from the tops to the bases of said panels and the angle between contiguous panels being a function both of the angle between juxtaposed faces of the frame and the angle between the two contiguous sides of the frame.
13. In a blank of stiff, tough sheet material from which a polygonal straight-sided picture frame can be fabricated: two end-to-end sets of contiguous trapezoidal panels adapted when assembled to form the front portions of two adjacent sides of the frame, each front portion being V-shaped and having two flat faces of substantially equal width, straight crease lines parallel to and midway between the tops and bottoms of the panels and dividing the panels into two sections, each section being adapted to form a face of that front portion which corresponds to the panel of which said section comprises a part, a straight crease line connecting the ends of the contiguous panels, said crease line extending uninterruptedly from the tops to the bases of said panels and the angle between contiguous panels being a function both of the angle between juxtaposed faces of the frame and the angle between the two contiguous sides of the frame.
